STOKER

William Thompson Hanna, Cincinnati, Ohio

Original application June 18, 1928, Serial No. 286,222. Divided and this application May 10, 1934, Serial No. 724,838. Renewed November 23, 1936. In Canada June 17, 1929

2 Claims. (Cl. 110—101)

This invention pertains to mechanism for distributing fuel over a fire bed. Although the embodiment of the invention chosen for illustration is adapted particularly for distribution of coal, and the like, over the fire bed of a locomotive, the invention is adapted for dispersing and distributing solid particles of other kinds and for other purposes.

This application is a division of my co-pending application Serial Number 286,222, filed June 18, 1928.

In stokers for spreading fuel over the fire bed of a locomotive, the fuel usually flows from the locomotive tender to a hopper located there beneath and thence through a conduit, or passageway, to the fire box. From the mouth of this passageway the fuel is spread as uniformly as possible over the entire area of the fire bed by fuel distributing mechanism preferably employing a fluid blast as fuel-impelling, or conveying, means. This distributing mechanism is located relatively close to the fire bed, and so being exposed to the intense heat of the fire is subjected to damaging effects to which other parts of the stoking mechanism are not exposed. Such being the case, it is desirable to make parts subject to the damaging effects of the high temperature readily replaceable in the event of damage. It is one of the objects of this invention to provide for such replacement.

However, fire boxes in different locomotives vary in dimensions. For example, the inclinations of the back heads vary and also on one locomotive the distributing mechanism may necessarily be located relatively low in a long fire box, while in another it must be located relatively high in a shorter fire box. In each, the manner in which the fuel is impelled from the distributing mechanism will necessarily be different. Another variable which enters into the distribution of the fuel is the nature and condition of the fuel itself. During a single "run" of a locomotive, at one time the fuel may be wet and sticky, at another time dry and powdered, and at another time filled with relatively large lumps. To compensate for these variations, it is desirable to provide for adjustment of certain of the parts of the distributing mechanism so that a stoker model may be adjusted to supply various types of fire boxes, and to operate on fuel having different characteristics as to size, moisture content, etc. It is another object of this invention to provide for such adjustment of parts of the distributing mechanism.

Other objects will be in part obvious and in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings, in which are shown one or more of the various possible embodiments of this invention,

Figure 1 is a vertical section of a stoker taken along a longitudinal line and showing (also in vertical section) distributing mechanism embodying the invention;

Figure 2 is a top horizontal section of Figure 1 taken on line 2—2 of Figure 1 and showing the distributing mechanism in top plan;

Figure 3 is an enlarged top plan view of a distributing plate and blast chamber shown in Figure 1, showing the cooperative relation of the one to the other;

Figure 4 is a front elevation of the parts shown in Figure 3 as viewed from inside the fire box;

Figure 5 is a side elevation (certain parts being shown in section) of the parts shown in Figure 3 and their relation to the spillway of the fuel housing, showing the distributing plate in its advanced or forward position; and,

Figure 6 is similar to Figure 5 except that the distributing plate is in recessed position.

Corresponding reference characters refer to corresponding parts throughout the several views of the drawings.

Referring to Figures 1 and 2, a fire box is generally indicated at 1 having the usual back head 3 provided with a firing opening 5 embraced by a fuel supply housing 7 which is part of the mechanical stoking mechanism described in my aforementioned copending application. Fuel coming from a source of supply, not shown, is forced to rise through an elevating conduit 9 to housing 7 and to flow through the firing opening under the influence of screw conveyer 11 located within the conduit.

Mounted within the housing are fuel conditioning and regulating means comprising worms 14 and 15. As described in my aforementioned application, these worms thin out and regulate the flow of the fuel to the firing opening so that it flows therethrough in a regulated stream. The conveyer 11 and the fuel conditioning means are driven through suitable gearing by means of a motor generally indicated at 16.

The mechanism just described insures the passage of fuel entering the housing 7 from the elevating conduit 9 over the ledge, or spillway, 8, in an even stream, from whence it flows upon and 5 over a blast chamber generally indicated at 18 and forming part of fuel distributing mechanism generally indicated at 17.

While in the embodiment illustrated the conduit 9 is shown as delivering fuel to the firing 10 opening 5, it is to be understood that the conduit may be of the type entering the fire box independently of the firing opening 5 in which event the distributing mechanism 17 associated with the mouth of the conduit would be located 15 entirely within the fire box.

The blast chamber 18 is provided with a plurality of fingers 19 through which jets of relatively high pressure steam may be directed. As shown in Figure 4, the top portions of the fingers 19 20 slope downwardly and forwardly into the fire box, and, in effect, form a grating, the fingers 19 forming the ridges of the grating, and the openings 119 forming the openings between the ridges or fingers 19. With this arrangement, fuel flowing over the grating formed by the fingers 19 is, in effect, screened, the larger particles riding over the fingers and the smaller particles of the fuel falling through the elongated openings 119.

Further, the fingers 19 are arranged in a fan- 30 formation whereby the openings 119 between the fingers diverge thereby eliminating any tendency for particles of fuel to become wedged between the fingers 19.

Likewise, the jets of steam directed into the 35 fire box through the fingers 19 are directed in a fan-formation to enable the distributing device, comprising the blast chamber 18 and a distributing plate (generally indicated at 31), to distribute the fuel over all portions of the fire bed. Referring to Figures 3, 4 and 5, a plurality of other 40 series of jets 20 and 21 are also provided in the chamber 18 arranged to the right and left sides of the fingers 19, and in a lower plane. Still another opening 22 is provided in the blast chamber 18 and is arranged in the form of a slit, 45 which gives a blast in the form of a ribbon. I find it preferable to supply the jets issuing from the fingers 19 with high pressure steam whereby the larger lumps falling over the ends of the 50 fingers 19 may be effectively carried to the proper place in the fire box, and, as will be hereinafter described, I find it preferable to supply the jets 20, 21 and 22 with steam of a lower pressure. However, under certain conditions of operation 55 I may find it desirable to vary these arrangements of high and low pressure steam.

The blast chamber 18 is provided with arms 18^a and 18^b which serve as conduits for the passage of the steam, and by means of which the said 60 chamber is pivotally supported in the side walls of the housing 7 by pipe sections 23 and 24 which are secured respectively in the side walls thereof and which pivotally support the respective arms 18^a and 18^b. Said pipe sections are coupled to 65 the high and low pressure steam lines by unions not shown. If at any time it is desired to temporarily displace the blast chamber 18 from the fire box, it may be turned backwards through the firing hole swinging around the pivots 23 and 24 and caused to rest upon the top of the coal in the housing 3.

Immediately below the blast chamber 18 in the fire box is the distributor plate 31, normally stationary but slidably mounted for adjustment, by 75 means of extensions 31^a resting upon lugs 32,

Figures 2 and 5, projecting from the housing 7 and additionally supported by the lugs 31^b, which bear against lugs 33, also projecting from the housing 7, Figures 1 and 5.

The blast chamber 18 rests on the distributor plate 31, and by means of its pivoted arrangement serves to lock it in position, that is, serves to prevent its being inadvertently raised from the supporting lugs 32 and 33. However, when it is desired to remove the distributing plate from the fire box, or for any other reason to raise it from the lugs 32 and 33, this may be accomplished by first turning back the blast chamber 18 by swinging it around the pivots 23 and 24 15 to free the plate 31 and then raising the plate from the lugs 32 and 33.

The distributor plate 31 is of a design which serves to distribute the fuel over the fire bed in an efficient manner, and particularly as regards 20 the back corners of the fire box, which sections of the fire bed are reached mainly by means of the channels 31^c. I further increase the efficiency 25 of the distributing device by the particular arrangement of surfaces 31^d and 31^e as shown. It is preferable to form the surface 31^d in a substantially horizontal plane and in such a position 30 that steam jets striking the plate 31^d are deflected therefrom, thereby carrying particles of fuel thereon over the channel 31^c to deposit the fuel immediately in front of the distributing device.

I prefer to form the surface 31^e inclining slightly forwardly and downwardly into the fire box whereby steam issuing from the jets 19 and 20 (the steam jets expanding along their median lines) do not strike the plate or surface 31^e in such a way as to cause the steam jets to deflect therefrom. Consequently any tendency for the jets to carry fuel upwardly and into the stack is substantially offset by this arrangement of the 40 surface 31^e. In other words, the arrangement of the plate 31^e in such a manner causes the steam jets issuing from the blast chamber to remain approximately parallel with the fire bed thereby to carry more effectively the fuel straight out 45 over it.

The surface 31^e of the distributor plate 31 is positioned beneath the grating formed by the fingers 19, and accordingly the finer fuel particles falling between the fingers 19 fall there; thus the surface 31^e coacts with the blasts of steam issuing from the slit 22 to efficiently and uniformly distribute the finer particles over the fire bed. In like manner, the channels 31^c coact 55 with the low pressure jets 20 and 21 to scatter and distribute fuel into the near corners of the fire box.

In order that the distributor plate may serve to cover more effectively the back corners of the fire bed, and in order that the distributing mechanism may be adapted to various widely different types of fire boxes, its position longitudinally of the fire bed may be varied by means of crank shaft 34, Figure 1, suitably journaled in bearings on the housing 7 and having a handle 34^a and an arm 35 keyed therewith which latter is linked to the distributor plate by means of the link 36. The advanced or forward position of the distributor plate is shown in Figure 5, and a receded position thereof is shown in Figure 6. With the 70 distributing plate advanced to its forward position, fuel is caused to travel a greater distance from the distributing plate, while in its back-most position, the fuel is allowed to fall to the fire bed at a shorter distance from the plate. In- 75

termediate positions of the plate produce corresponding effects.

I have also provided means for cooling the distributor plate. To this end the blast chamber is provided with extensions 18^c which are chambered to connect with one of the steam conduits and each of said extensions is provided with one or more openings 66 whereby jets of steam may be suitably directed to the underneath side of said distributor plate.

With this novel construction and arrangement of the blast chamber 18 and distributing plate 31, I accomplish new and highly advantageous results. For example, as the mass of fuel (which 15 consists of a heterogeneous mixture of large and small particles) flows over the ledge 8 onto the blast chamber 18, the fingers 19 act to screen the fuel to separate the larger from the smaller particles whereby the larger particles flowing over 20 the ends of the fingers are picked up by the high pressure jets of steam issuing therefrom and are carried to the far parts of the fire bed, but are not carried out of the fire box into the stack of the locomotive, the steam pressure being controlled to prevent such operation. The smaller 25 particles falling between the fingers onto the surface 31^e do not immediately come into contact with the high pressure jets, but are picked up by the low pressure ribbon jet of steam issuing from the jet 22 and are swept over the surface 31^e and are thus carried effectively to all parts of the fire box without being carried out of the stack by the high pressure jets. As the low pressure 30 jets expand upwardly, and the high pressure jets expand downwardly, the two meet in a neutralizing 35 zone, which also aids in the desired distribution of the finer particles over the fire bed.

One of the elements tending to perfect this unique and highly advantageous distribution of 40 the finer particles over the fire bed is the particular construction of the surface 31^e and its particular relative position with respect to the low pressure steam jet 22, for this arrangement

and construction serves to govern the ultimate course which the finer particles are to take.

As various embodiments might be made of this invention, and as various changes might be made in the construction herein described, all without departing from the scope of the invention, it is to be understood that all matter herein set forth or shown in the accompanying drawings is to be interpreted as illustrative and not in a limiting sense.

I claim:

1. In combination with a furnace having a backhead provided with a firing opening, a housing embracing said opening, a distributor plate slidably seated in said opening, means for slidably adjusting said plate, a blast chamber so seated on said plate as to prevent its removal from operative position, said blast chamber being provided with openings adapted to discharge across said plate, and hollow arms secured to the respective ends of said blast chamber and communicating therewith, said arms being pivotally connected with said housing in such a manner that said blast chamber can be swung thereon from its position in said opening.

2. In combination with a furnace having a backhead provided with a firing opening, a housing having an opening communicating with said firing opening, a distributor plate adjustably resting in said firing opening on supports, means for adjusting said plate to change the distribution of fuel, a blast chamber so seated on said plate as to prevent its accidentally moving from operative position on said supports, said blast chamber being provided with openings adapted to discharge across said plate, and hollow arms secured to the respective ends of said blast chamber and communicating therewith, said arms providing mounting means for pivotally mounting said blast chamber with respect to said housing so that the blast chamber can be swung from its position in said opening.

WILLIAM THOMPSON HANNA.
